UNITED STATES PATENT OFFICE.

AUGUST HAFERKAMP, OF WALLIS, TEXAS.

MOLDBOARD AND LANDSIDE PLOW AND GAGE-WHEEL.

1,148,838.

Specification of Letters Patent.

Patented Aug. 3, 1915.

Application filed June 17, 1914. Serial No. 845,625.

To all whom it may concern:

Be it known that I, AUGUST HAFERKAMP, a citizen of the United States, residing at Wallis, in the county of Austin and State of Texas, have invented certain new and useful Improvements in a Moldboard and Landside Plow and Gage-Wheel; and I do hereby declare the following to be a full, clear, and exact description of the invention, such as will enable others skilled in the art to which it appertains to make and use the same.

My invention relates to attachments for middle bursting plows whereby I can adjustably operate the plow to any suitable depth.

The main object of my invention is an attachment whereby I can quickly adjust the depth of my plow into the ground.

Another object of my invention is to provide a sliding fulcrum arrangement to operate the depth of the standard.

Still another object is to provide an arrangement whereby the reach of the operating means can be adjustably connected.

Other objects and advantages of this invention will be hereinafter more clearly set forth in the specification and pointed out in the claims.

Similar characters of reference refer to similar parts throughout the specification and drawing in which the figure is a perspective elevation of my attachment as applied to a middle bursting plow.

In the drawing, 1 is my plow beam of ordinary construction, 2 my plow attached to the beam, said plow being likewise of ordinary construction, 3 a handle to my plow also of the ordinary construction, said handle being braced to said plow beam by means of the usual braces such as 4.

Attached to the forward end of my plow beam is my clevis construction 5 composed of two oppositely disposed side plates 15, said plates matching each other in structure and being clamped on the opposite sides of the plow beam 1 by means of bolts 16 or other suitable forms of fastening devices.

Running through a suitable aperture formed in the side plates 15, is a standard 17, said standard having free vertical play in said clevis. The top end of my standard 17 is pivotally connected to a lever member 18, said lever member being of a substantially hook formation having a substantially arcuate slot 19 within the hook portion. A

bolt 20 runs through suitable apertures in the top portions of my clevis 5 and passes through said slot 19 to form the movable leverage pivot for said member 18.

Swivelly connected to the lower end of my standard 17 by means of the usual swivel mounting 21 is a gage wheel 22, said mounting 21 having a pair of oppositely matched members with apertures near the ends thereof, through which runs my axle 23, said axle having bushing bearings 24 placed on each side of my gage wheel and between the arms of the mounting 21. If desired I attach a mud scraper 25 to my gage wheel 22 by means of a thumb screw 26, said thumb screw working in a slot 27 to allow of suitable adjustment of said scraper. Said standard is operated into vertical movement through the clevis 5 by means of said member 18, a friction pulley 28 being attached to the lower rear edge of my clevis and operating against the standard to reduce friction. My leverage member 18 is operated to adjust said standard 17 by means of a link 29 and a reach rod 30, said reach rod being connected to a lever arm 31, which has the usual sliding locking members 32 working within the teeth of a quadrant 33 mounted upon the plow beam 1, to which the lever 31 is pivotally connected at the focal point of said teeth. Thus manipulating my lever 31, I operate my leverage member 18 through the medium of the reach rod 30, my standard 17 adjusting according to the height with which I desire my plow to operate.

My reach rod which as before stated, is connected to the lever 31, is composed of a bar having a right angular bent end 34, said end having an aperture running therethrough, through which a connecting link 35 is passed, said link having a bent end 36 that is adjustably positioned in suitable apertures in my reach rod 30 so that said reach rod can be lengthened according to the plow on which it is mounted.

The end of my link 35 is threaded as at 37 and suitably seated, as shown in dotted lines at 38 of the figure, in the link member 29. By this arrangement I can obtain the proper breaking of the ground and the proper depth of said breaking in a convenient, easily operated, and simple manner.

Having now described the preferred embodiment of my invention, what I desire to secure by Letters Patent is:—

1. A device of the character described

comprising a plow beam, a two part clevis carrying a transverse fulcrum bolt mounted upon said beam, a standard carrying a gage wheel vertically operating in said clevis, a 5 substantially arcuate shaped operating lever having an arcuate centrally disposed slot in the outer end thereof pivoted to the upper end of said standard, said fulcrum bolt of said clevis operating through said slot, a 10 link member pivoted to the inner end of said operating lever, a connecting member threaded into said link member having the inner end thereof at right angles to the body portion of said link member, a reach rod 15 having the end portion thereof bent at right angles and mounted upon said connection, the angular portion of said connection seated in a suitable aperture of said reach rod, and means mounted upon the rear end of 20 said beam and pivoted to said reach rod adapted to operate said lever to raise and lower said standard.

2. A device of the character described comprising; a plow beam having a two part 25 clevis mounted upon the end thereof, said clevis having a fulcrum member mounted in the upper end thereof, a slotted actuating

lever slidingly playing upon said fulcrum member, actuating means, adjustable connecting means between said actuating means and said lever, and a standard having an angular base portion carrying a gage wheel, said standard adjustably mounted between the parts of said clevis and pivoted to said lever to be vertically adjusted upon the actuation of said lever. 35

3. A device of the character described comprising; a standard carrying a gage wheel, an actuating lever pivoted to said standard, and, a plow beam carrying a 40 clevis, said clevis adjustably mounting said standard and supporting said actuating lever, means to actuate said lever mounted upon said beam to adjust the position of said standard and threaded angular bent means 45 positioned in said actuation means, adapted to adjust the reach rod thereof.

In testimony whereof I have signed my name to this specification in the presence of two subscribing witnesses.

AUGUST HAVERKAMP.
